CLAIM

The ornamental design for a housing part for a coin dispenser, as shown and described.

DESCRIPTION

FIG. 1 is a top front perspective view of a housing part for a coin dispenser, showing our new design;

FIG. 2 is a bottom rear perspective view thereof;

FIG. 3 is a right side elevational view thereof; and

FIG. 4 is a cross sectional view thereof taken on line 4—4 of FIG. 2.

FIG.1.

FIG.3.

FIG.4.
